FIG.4

FIG.3

FIG.5

FIGURE 1 is a top plan view of a handle for electrically operated toothbrushes or the like embodying my new design;

FIGURE 2 is a side view of the same;

FIGURE 3 is a bottom plan view of the same;

FIGURE 4 is another side view of the same turned 90° on its axis from that shown in FIGURE 2; and

FIGURE 5 is another side view of the same turned 180° on its axis from that shown in FIGURE 2.

The broken line showing of a toothbrush in FIGURE 4 is for illustrative purposes only.

I claim:

The ornamental design for a handle for electrically

operated toothbrush or the like, substantially as shown and described.
